(57) **CLAIM**

The ornamental design for a plant watering device as shown and described.

DESCRIPTION

FIG. 1 is a perspective view of a plant watering device showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the plant watering device where the plant watering device is in a configuration of use. The broken lines in the drawings depict portions of the plant watering device that form no part of the claimed design.
